P. J. KENT

AUTOMOBILE INSTRUMENT PANEL

Filed April 1, 1927

INVENTOR
PHILIP J. KENT.
BY
John Barnes
ATTORNEY

UNITED STATES PATENT OFFICE.

PHILIP J. KENT, OF ROYAL OAK, MICHIGAN, ASSIGNOR TO CHRYSLER CORPORATION, OF DETROIT, MICHIGAN, A CORPORATION OF DELAWARE.

DESIGN FOR AN AUTOMOBILE INSTRUMENT PANEL.

Application filed April 1, 1927. Serial No. 21,427. Term of patent 14 years.

To all whom it may concern:

Be it known that I, PHILIP J. KENT, a citizen of the United States, residing in the city of Royal Oak, in the county of Oakland and State of Michigan, have invented a new, original, and ornamental Design for an Automobile Instrument Panel, of which the following is a specification, reference being

had to the accompanying drawing, forming a part thereof, in which the figure is a front elevation view showing my new design.

What I claim is:

The ornamental design for an automobile instrument panel, as shown.

PHILIP J. KENT.
